UNITED STATES PATENT OFFICE

155,344

DESIGN FOR A SOAP BUBBLE DEVICE

Sten Johanson, New York, N. Y.

Application August 2, 1946, Serial No. 132,221

Term of patent 7 years

(Cl. D34—15)

To all whom it may concern:

Be it known that I, Sten Johanson, a citizen of Sweden and a resident of the city of New York, county of New York, State of New York, have invented a new, original, and ornamental Design for a Soap Bubble Device, of which the following is a specification, reference being had to the accompanying drawing, forming part thereof, in which:

Fig. 1 is a perspective view of a soap bubble device, showing my new design.

Fig. 2 is a side elevation of the same.

Fig. 3 is a rear elevation view of the same.

I claim:

The ornamental design for a soap bubble device, as shown.

STEN JOHANSON.
